UNITED STATES PATENT OFFICE

139,037

DESIGN FOR A PUNCH PRESS OR SIMILAR MACHINE

Philip E. Wilcox, New York, N. Y., assignor to
Standard Machinery Company, Cranston, R. I.,
a corporation of Rhode Island

Application May 16, 1944, Serial No. 113,615

Term of patent 14 years

(Cl. D63—1)

To all whom it may concern:

Be it known that I, Philip E. Wilcox, a citizen of the United States, residing at New York city, in the county and State of New York, have invented a new, original, and ornamental Design for Punch Press or Similar Machine, of which the following is a specification, reference being had to the accompanying drawings, forming a part thereof.

Fig. 1 is a perspective view showing the front

and one side of a punch press or similar machine embodying my new design; and

Fig. 2 is a perspective view showing the rear and other side thereof.

The dominant features of the design reside in the portions shown in full lines.

I claim:

The ornamental design for a punch press or similar machine, as shown and described.

PHILIP E. WILCOX.
